UNITED STATES PATENT OFFICE.

WILLIAM MATLOCK CAMPBELL, OF HONOLULU, TERRITORY OF HAWAII.

DISH-WASHING MACHINE.

No. 833,440.

Specification of Letters Patent.

Patented Oct. 16, 1906.

Application filed January 25, 1906. Serial No. 297,770.

To all whom it may concern:

Be it known that I, WILLIAM MATLOCK CAMPBELL, a citizen of the United States, residing at Honolulu, Territory of Hawaii, have invented new and useful Improvements in Dish-Washing Machines, of which the following is a specification.

My invention relates to dish-washing machines. Its object is to provide a machine which will wash, rinse, and dry dishes and discharge the same from the machine in one operation and without the intervention of manual means further than that required to insert the dishes into the machine.

15 In my apparatus plates and like dishes are stood on edge and made to revolve through a succession of washing and rinsing baths and through a drier. In order to make the machine complete, provision is made for 20 washing all sorts of dishes other than plates, as well as knives, forks, spoons, &c.

The invention consists of the parts and the construction and the combination of parts, as hereinafter more fully described and 25 claimed, having reference to the accompanying drawings, in which—

Figure 1 is a plan view of my improved dish-washing machine. Fig. 2 is a side elevation, partially in section, of the same. Fig. 30 3 is a plan view of the spiral runway. Fig. 4 is a diagrammatic view of the runway in rectilinear projection. Fig. 5 is an underneath sectional view of the tray-feed.

A represents a table or stand of any suitable size and description, and 2 is a drum disposed beneath the table and suitably mounted to revolve on a vertical axis and operated by any suitable means from any suitable source of power, as the motor 3. 35 This drum is provided with a spiral runway 4, into which the dishes are inserted through an opening 5 in the top of the table. The plates are made to traverse the runway by revolving the drum and supporting the edge of the 40 plate in opposition to the drum, as by means of the roller 6, which is suitably mounted on a stationary part of the apparatus.

The runway 4 is provided with an undulating bottom, the upraised portions 7 8 of 45 which divide the runway into a plurality of successively-arranged compartments *a b c*, adapted for washing, rinsing, and drying purposes. The plate is first inserted through the opening 5 into that portion *a* of the runway nearest the center of the compartment. 50 The runway is made purposely narrow, so as

to support the plate upright on its edge. By a revolution of the drum and the suitable supporting of the top edge of the plate, as by the roller 6, the plate is made to revolve on 60 its axis and is gradually worked to the outside of the drum and finally discharged through an opening 9 in the bottom of the runway and into a suitable receptacle 10. The bottom of the runway is preferably V- 65 shaped and may be lined with rubber or other suitable soft resilient material 4' to protect the plate against injury and to offer sufficient friction to cause the plate to rotate.

The receptacle or box 10 is mounted on 70 rollers or otherwise adapted to slide on suitable guides 11. It is provided with a number of partitions and is given a step-by-step movement corresponding with the revolution of the drum, so that the space between 75 the several partitions will be brought successively into line with the slot 9 to receive the plate as it is delivered from the drum. Any appropriate means may be employed to effect this coördinate movement of the receptacle and drum. As here shown, one edge of 80 the receptacle is provided with a rack 12, and the drum has an eccentric cam 13, which engages the teeth of the rack 12 successively to advance the receptacle one plate-space at 85 each revolution of the drum. There may be a plurality of these receptacles provided, so that as one is filled another may be slid into place to receive each plate as it is delivered from the machine. 90

In order to allow for the proper entry of plates into the machine and their delivery therefrom, it is preferred to give the drum an intermittent movement permitting it to stop each time the discharge-opening 9 comes 95 over the receptacle 10. Any suitable means may be employed to produce this intermittent or step-by-step movement of the drum. I have shown by way of illustration a mulated gear connection 14 between the motor 100 2 and the drum to effect the desired result.

The walls of the runway in the various compartments *a b*, and *c* are provided with suitable rubbers corresponding to the particular functions which they are to form. In the 105 compartment *a* the walls are lined with soft rubbing-surfaces 15, made of sponge, felt, soft cloth, or other suitable material, bolted or otherwise secured in position and operating on the soiled surfaces of the plate to remove 110 every vestige of dirt. The rinsing compartment may or may not be provided with rub-

bers. The drying-compartment *c* is lined with suitable soft absorbent material 15', and this lining is so arranged on the walls that each plate will be thoroughly dried during its passage from the rinsing-compartment *b* to the discharge-slot 9 in the drum.

In operation a plate to be washed is inserted into the machine through opening 5 in the top of the table at the proper moment, 10 which according to the present description is during the period of rest of the drum. Preferably the plate is inserted with its concavity toward the center of the machine, so that the cleansing-surfaces 15 on the adjacent wall of 15 the runway will engage the concavity of the plate tangentially, and as the plate and drum revolve simultaneously every portion of the plate to be cleaned will be acted upon by the brushes. Passing through the washing-bath 20 the plate rises on the undulation 7 and drops into the rinsing-water contained in compartment *b*, through which the plate is passed prior to being dried. It then rises on the undulation 8 and enters the drying-chamber *c*, 25 whence it is finally discharged into the receptacle 10. The inside of the drum within the space inclosed by the inner walls of the runway forms a chamber 17, having a conical bottom and a central discharge 18. This 30 chamber contains a screen or equivalent dish-support 19, on which cups, saucers, and like dishes which need only to be rinsed may be placed, inverted above a rotary sprinkling device 20, connected with any suitable source 35 of hot-water supply. The top of the table A is provided with a hinged cover 21, which may be lifted to give access to the chamber 17. This cover is closed to keep in the splash during the operation of the sprinkler. A 40 strip 22, carried by the drum, may underlie the crack around the cover to deflect water from the sprinkler and prevent leak around the lid 21. The shaft of the drum is shown as hollow and is stepped in a bearing which 45 has a discharge-outlet registering with the previously-mentioned passage-way 18. By turning off the water to pipe 20', by which the sprinkler is run, the dishes will quickly dry by their own heat and the contained heat of 50 the chamber. The water from the washing and rinsing compartments *a b* of the runway 4 may be discharged into the chamber 17 and through suitable valved connections 23. Water for the compartments *a b* may be delivered through the valved inlet-pipe 24.

In order to make the machine complete and adapted for washing dishes and pots of various descriptions, I provide a sink portion 25, in which I arrange a suitably-mounted rotary brush 26, which is disposed radially to and driven from the drum 2, the rotation of the brush 26 being effected by the interengagement of the gear 27 with the annular rack 28 on the upper edge of the drum. 55 The brush 26 is of special use in cleaning

deep dishes—such as pitchers, pots, kettles, and the like—and brushes of various descriptions may be employed on the same stem for either scrubbing, scraping, or drying purposes.

For the purpose of washing knives, forks, and the like I provide two rollers 29, having suitably-opposed rubbing or brush surfaces. These rollers are mounted on a fixed part of the machine-frame and are rotated by any 70 appropriate means. I have here shown them as driven from the shaft of brush 26 by means of the intermeshing gears 30.

It is possible that various modifications in my invention may be made without departing from the principle thereof, and I do not wish to be understood as limiting myself to my specific construction beyond what is required by a reasonable interpretation of my claims.

Having thus described my invention, what I claim, and desire to secure by Letters Patent, is—

1. A dish-washing machine having a horizontally-revolvble drum with a spiral runway formed with a series of successively-arranged chambers for washing, rinsing and drying purposes, and means coacting with said drum for passing dishes successively through said chambers and delivering them 95 from the machine.

2. In a dish-washing machine the combination of a horizontally-revolvble drum having a spiral runway formed with successive washing and drying chambers, means 100 for holding the dishes relative to the movement of said drum, whereby they are caused to pass through the washing and drying chambers of the drum, and means permitting the dishes to be delivered from the drying- 105 chamber.

3. In a dish-washing machine, the combination of a single revoluble drum having a spiral runway with successively - arranged compartments, one of said compartments 110 adapted to contain water, drying devices associated with the other compartment, means whereby the dishes are held relative to the movement of the drum and thereby caused to pass successively through said 115 compartments and in contact with said drying devices.

4. In a dish-washing machine, the combination of a drum revoluble in a horizontal plane and provided with a spiral runway, 120 said runway having a water-containing compartment and a drying-compartment, said drying-compartment provided with drying devices, and means for holding the dishes relative to the travel of the drum whereby 125 the said compartments successively pass the dishes, said drum having a discharge-opening through which the dishes are discharged when brought into register therewith.

5. In a dish-washing machine, the combi- 130

nation of a drum rotatable in a horizontal plane, and provided with a water-containing compartment, and a table having a feed-inlet by which the dishes are delivered onto the drum, means for holding the dishes relative to the rotation of the drum whereby the water-containing compartment is caused to pass the dishes, said drum having, also, a discharge-opening through which the dishes are automatically delivered when brought into register therewith.

6. In a dish-washing machine, the combination of a drum, a vertically-disposed shaft therefor, said drum being provided with a water-containing compartment, a table having an opening through which a dish may be inserted and supported on edge on the drum, and means for holding the dish relative to the travel of the drum but allowed to rotate on its axis.

7. In a dish-washing machine, the combination of a drum rotatable in a horizontal plane and provided with a water-containing compartment, a table beneath which the drum rotates, said table having an opening through which a dish may be inserted edgewise and supported on the drum, said drum having a discharge-opening through which the dish is delivered when said discharge-opening is brought into register with the dish.

8. In a dish-washing machine, the combination of a drum revoluble on a vertical axis, and having a spiral runway for the receipt and support of a dish on edge, and means coöperating with the drum for holding the dish against travel with the drum but allowing the dish to rotate on its own axis through said runway.

9. In a dish-washing machine, the combination of a drum revoluble on a vertical axis, said drum having a spiral runway for the receipt and support of a dish on edge, means coöperating with the drum for holding the dish against travel with the drum but allowing said dish to rotate on its own axis, said drum having an opening which is brought into register with the dish and through which opening the dish is delivered from the runway.

10. In a dish-washing machine, the combination of a drum revoluble on a vertical axis, said drum having a spiral runway for the receipt and support of a dish on edge, means coöperating with the drum to cause a dish to traverse the runway and to rotate on its axis, said drum having near the end of the runway a delivery-opening adapted to be brought into register with the dish, said runway having a soft lining engageable with the dish in the passage of the latter through the runway.

11. In a dish-washing machine, the com-

bination of a rotatable drum having a series of successively-arranged compartments, certain of said compartments adapted to contain water, drying means in one of the compartments, and means coöperating with the drum to cause a dish to traverse said compartment and to rotate on its axis.

12. In a dish-washing machine, the combination of a rotatable drum having a series of successively-arranged compartments, certain of said compartments adapted to contain water, drying means in other of the compartments, and roller means coöperating with the drum to cause a dish to traverse said compartments and to rotate on its axis.

13. In a dish-washing machine, the combination of a rotatable drum having a series of successively-arranged compartments, certain of said compartments adapted to contain water, drying means in other of the compartments, means coöperating with the drum to cause a dish to traverse said compartments and to rotate on its axis, said drum having means permitting of the automatic delivery of the dish from the drying-compartment, and a receiver for the dried dishes.

14. The combination with a drum rotatable in a horizontal plane and having an opening through which dishes are delivered after being washed, of a receiver positioned in line below said opening and adapted to receive the dishes on edge and means whereby the receiver is given a step-by-step movement.

15. A dish-washing machine comprising a drum revoluble on a vertical axis, said drum having a centrally-located chamber and having a runway spirally arranged from the inner portion outwardly, a sprinkling device arranged in said chamber, and dish-supporting means in the chamber in relation to the sprinkler.

16. In a dish-washing machine, the combination of a drum revoluble on a vertical axis and having a runway of volute form, means for holding the dish relative to the drum to cause the dish to traverse said runway, and to rotate on its axis.

17. In a dish-washing machine, a rotatable drum revoluble on a vertical axis and having a runway of volute form, rubbers on the sides of the runway, and means for holding a dish relative to the drum whereby the dish rotates in the runway on the rotation of the drum.

In testimony whereof I have hereunto set my hand in presence of two subscribing witnesses.

WILLIAM MATLOCK CAMPBELL.
